DES. 2289

William H. Carter, of Cincinnati, Ohio,
Letters Patent No. 2289. Dated April 3^d 1866.
Design for an Alphabet of Letters.

The schedule referred to in these Letters Patent and making part of the same,

To all whom it may concern:

Be it known that I, William H. Carter, of Cincinnati in the County of Hamilton and State of Ohio, have invented a new ornamental Design for Letters and Numerals, and I do hereby declare the following to be a full and exact description thereof, reference being had to the accompanying drawings which are made a part of this specification.

My said invention consists in applying to the upper and lower end of each stem of each letter and numeral a representation of the national shield of the United States with stripes extending horizontally from it in both directions, as shown in the drawings.

I claim as new and desire to secure by Letters Patent, The ornamental Design for Letters and Numerals, represented in the accompanying drawings.

In testimony of which Invention, I hereunto set my hand.

Witnesses.
